CLAIM

We claim the ornamental design for a tabletop remote load control device, as shown and described.

DESCRIPTION

FIG. 1 is a perspective view of a tabletop remote load control device according to a first embodiment of our new design. FIG. 2 is a front view of the embodiment depicted in FIG. 1. FIG. 3 is a left side view of the embodiment depicted in FIG. 1.

FIG. 4 is a right side view of the embodiment depicted in FIG. 1. FIG. 5 is a top view of the embodiment depicted in FIG. 1. FIG. 6 is a bottom view of the embodiment depicted in FIG. 1.

FIG. 7 is a perspective view of a tabletop remote load control device according to a second embodiment of our new design. FIG. 8 is a front view of the embodiment depicted in FIG. 7. FIG. 9 is a left side view of the embodiment depicted in FIG. 7.

FIG. 10 is a right side view of the embodiment depicted in FIG. 7. FIG. 11 is a top view of the embodiment depicted in FIG. 7; and,

FIG. 12 is a bottom view of the embodiment depicted in FIG. 7.

The rear views form no part of the design and are omitted. The portions of the drawings appearing in broken line are for environment only and do not form a part of the claimed design.

1 Claim, 8 Drawing Sheets
